UNITED STATES PATENT OFFICE.

CALVIN A. SHIVE, OF PAYSON, OKLAHOMA, ASSIGNOR, BY MESNE ASSIGNMENTS, TO
J. S. HOUT, OF TULSA, OKLAHOMA.

GEARING FOR WASHING-MACHINES AND THE LIKE.

1,143,326.

Specification of Letters Patent.

Patented June 15, 1915.

Application filed June 7, 1909. Serial No. 500,659.

To all whom it may concern:

Be it known that I, CALVIN A. SHIVE, citizen of the United States, residing at Payson, in the county of Lincoln and State 5 of Oklahoma, have invented certain new and useful Improvements in Gearing for Washing-Machines and the like, of which the following is a specification.

This invention relates to washing machines and my object is to produce a washing machine embodying a perforated drum and automatic means for coöperating with the operator in oscillating the drum.

A further object is to produce a drum 15 composed of a body portion and two doors disposed at diametrically opposite points, one of which is detachable so that when it is removed and the other door is open, access 20 may be conveniently had to clean the tub or receptacle without removing the drum.

A still further object is to produce a machine of the character outlined which embodies the desirable features of simplicity, 25 strength, durability and cheapness of construction.

With these general objects in view the invention consists in certain novel and peculiar features of construction and organization 30 as hereinafter appears; and in order that it may be fully understood reference is to be had to the accompanying drawing, in which;—

Figure 1, is a side elevation of a washing machine embodying my invention. Fig. 2, 35 is a vertical section taken on the line II—II of Fig. 1. Fig. 3. is a section taken on the line III—III of Fig. 2. Fig. 4, is a perspective view of a part of the drum. Fig. 5, 40 is a side elevation of a modified construction of the machine.

In the said drawing, 1 indicates a tub or receptacle of substantially semicylindrical form mounted upon supporting legs 2 and provided with a drain hole 3 normally 45 closed by a plug 4, the cover 4^a being of arched form and hinged as at 4^b to a cross bar 4^c secured to and bridging one end of the tub or receptacle. Arranged within this 50 tub or receptacle is a preferably cylinder-shaped drum consisting of a body 5 having perforations 6 in its periphery, and the latter corrugated as at 7, though if the drum is made of wood as indicated, the corrugations by preference will only be on the inside as shown in Fig. 3, most clearly, the

end portions of the drum being also corrugated by preference as shown at 8. 9 and 10 indicate segment-shaped doors which fit against opposite edges of the end-portions of the body so as to conjointly form therewith a complete cylinder, the peripheral or curved portions of doors 9 and 10 being perforated at 11 and 12 respectively, the end-portions of said doors being likewise corrugated by preference, as at 16. The door 9 is 60 hinged at 17 to the body of the drum and is equipped with a pin 18 to be engaged by a hook 19 pivoted to the body. The door 10 is provided with hinge-hooks 20 for pivotal and detachable engagement with pins 21 65 projecting from brackets 22 secured to the body and at its free end is provided with a pin 23 to be engaged by a hook 24 pivotally carried by the body. When the hooks 24 are disengaged from pins 23, door 10 can be 70 swung open and if desired, can be detached from hinge-pins 21 by an obvious manipulation of the door.

25 are spider brackets secured to the end-portions of the body 5 and provided with 80 outwardly-projecting cylindrical trunnions 26 which extend through bearing brackets 27 secured to the side walls of the tub or receptacle, and secured upon the end of one of the trunnions is a small external-tooth 85 gear-wheel 28 which fits within and meshes with an internal-tooth gear-wheel 29 journaled on a stub-shaft 30 secured rigidly to the tub or receptacle vertically above wheel 28, and secured rigidly to said wheel 29 is 90 a handle or lever 31.

32 is a pin projecting outward from gear-wheel 29 in line with handle 31 and pivoted on said pin is a link 33, a spring-cotter 34 extending through said pin to hold the link 95 in position thereon.

35 is a pair of retractile springs secured at their neighboring ends to opposite ends of link 33 and at their opposite ends to the outwardly projecting arms 37 of a pair of 100 angle brackets 38, embracing the corners of the tub and secured rigidly to the same by screws 39.

The springs are of substantially equal 105 strength and therefore normally hold the handle 31 projecting vertically upward and the drum with its door 9 uppermost. With the parts arranged as described the door 9 can be easily opened and the articles 40 to be washed dropped into the drum. Boiling 110

water, containing a suitable washing compound, can then be poured into the tub or receptacle and it will, of course, seek its level in the drum through the perforations thereof and saturate the articles therein. The operator then grasps the handle and rocks the same in an obvious manner, preferably swinging the handle far enough toward each side to move the contents of the drum approximately to the position shown in dotted lines, Fig. 3, it being understood that when the handle is swung toward one side it tensions the retractile spring at the corresponding side and permits the other spring to relax, the oscillation of the drum, of course, being effected through the turning of the small gear-wheel by the large one secured to the handle. A comparatively slow movement of the handle imparts rapid movement to the drum, so that the articles therein shall acquire sufficient momentum by the time they are raised to the position shown in dotted lines, Fig. 3, to be projected in the direction indicated by the arrow, same figure, to the opposite side of the drum. The articles will impinge upon such side with sufficient force to continue the rotation of the drum for a slight distance without further effort on the part of the operator, this continued rotation continuing the movement of the handle in the same direction and increasing the tension of the tensioned-spring, which spring immediately retracts so as to start the reverse oscillation of the drum and handle, this reverse operation being assisted by the operator's pressure or pull on the handle. When the drum has been rotated in said reverse direction the proper distance, incidentally tensioning the originally relaxed spring and permitting the originally tensioned spring to relax, the articles through the momentum acquired jump to the opposite side of the drum and thus increase the extent of such reverse operation and the tension of the spring originally relaxed, all subsequent operations being repetitions of those described. From the foregoing it will be apparent that the actual labor entailed on the operator is small, as the articles being washed are utilized by increasing the tension of the springs alternately, to cause said springs to react strongly and thus perform the actual reversing operation of the drum, and leave the operator the duty only of continuing such operation for a suitable distance in each direction.

If desired to clean the tub or receptacle after the washed articles are removed and the water has been drained from the tub, the handle 31 is turned until the door 10 is uppermost to permit such door to be detached from the drum. The handle is then released and the tensioned spring retracts and revolves the drum back to its original position with the door 9 uppermost, which

door is then opened and the operator given access to the bottom of the tub or receptacle through the drum.

For convenience in removing the drum from the receptacle, the arms of the spider-brackets 25 are of such length as to project above the tub or receptacle as shown clearly in Figs. 1 and 2, so that the screws fastening said spiders to the body of the drum are conveniently accessible. After the normally exposed screws are removed, the handle is manipulated to turn the drum one-half revolution so as to expose the other two screws, as will be readily understood. By reversing these operations the drum can be resecured in the tub.

In the preferred construction disclosed by Fig. 5, the springs 35^a are arranged at diametrically opposite sides of gear wheel 29 and at their inner ends are attached to links 33^a pivoted to said wheel at points diametrically opposite from each other and equal distances from the handle 31, the outer ends of the springs being attached to the brackets 38 disposed in the horizontal plane of the axis of said wheel. When the handle 21 is operated both springs 35^a offer a yielding resistance and when the handle is released said springs coöperate in returning the handle and hence the drum to normal position. By this construction it is practical to employ springs of approximately half the strength of the springs employed in the construction shown by Fig. 1 as in the last-named construction, the springs alternately offer yielding resistance to the operation of the handle and do not coöperate in returning the handle to normal position.

Referring now to Fig. 5, it will be seen that the springs 35^a are arranged in the horizontal plane of the axis of wheel 29 and are pivotally connected at their inner ends to said wheel at diametrically opposite points and at their outer ends to the outwardly-projecting arms 37 of brackets 38, which in this figure are disposed in a higher plane than in Fig. 1. This arrangement of parts permits the use of lighter or weaker springs, as the springs coöperate in resisting movement of the handle away from a vertical position and in returning the handle to such position as distinguished from the construction shown by Fig. 1 where each spring resists movement of the handle away from the vertical and then assists in drawing it back to such vertical position. With the construction shown in Fig. 5 the spring offers practically no resistance in the initial part of the movement and the cylinder obtains an impetus which assists the operator in overcoming the resistance of the springs without exertion. In the construction shown by Fig. 1 the resistance of the springs is imposed suddenly at times to make the operation of the cylinder harder and less uniform.

From the above description it will be apparent that I have produced a washing machine embodying the features of advantage enumerated as desirable and which is susceptible of modification in some particulars without departing from the principle of construction involved.

Having thus described the invention what I claim as new and desire to secure by Letters Patent, is:—

A gearing for washing machines and the like, comprising a suitable support, a rotatable object journaled on said support connected axially thereto a gear, an internally-toothed gear wheel disposed eccentrically of and inclosing and meshing with

said gear, a handle secured to and projecting from said gear wheel whereby to oscillate the same, a link pivoted on said gear wheel at a point in line with said handle, and a pair of retractile springs connected at their opposite ends to said link and said support respectively and adapted to maintain said wheel with its handle normally in vertical position.

In testimony whereof I affix my signature, in the presence of two witnesses.

CALVIN A. SHIVE.
